UNITED STATES PATENT OFFICE.

FRANZ DEVENTER, OF HANOVER, GERMANY.

METALLIC PACKING-RING.

1,256,881.

Specification of Letters Patent. Patented Feb. 19, 1918.

Application filed March 19, 1914. Serial No. 825,915.

To all whom it may concern:

Be it known that I, FRANZ DEVENTER, a citizen of the German Empire, and residing at Hanover, German Empire, have invented 5 a new and useful Improved Metallic Packing-Ring, of which the following is a full, clear, and exact description.

The object of the present invention is to produce metallic packing rings by high 10 pressure. According to the invention a yielding and at the same time automatically lubricating packing ring is attained, suitable for all sorts of glands.

It has been proposed to form rings of this 15 kind from comparatively short metal pieces in the form of shavings or the like with the addition of asbestos fibers, graphite and similar materials, by compressing the same. Rings of this kind do not possess sufficient 20 strength and resistance.

According to the present invention the fundamental material consists of fibrous materials of long fiber, having sufficient length approximately to form the ring. In this 25 case, a metal is advantageously employed having but small frictional coefficient in comparison with cast iron, steel, bronze and the like, and of great flexibility.

Experiments have shown that fibrous 30 metal such as lead or a lead alloy, consisting of long, thin, flat fibers are most suitable for the purpose in view.

Metallic fibers of this kind are cut to a length corresponding approximately to the 35 size of the ring to be produced. These fibers are spread on a suitable flat surface and coated, as evenly as possible with a suitable highly refractory fatty preparation. The fibers thus prepared are then treated, also 40 as evenly as possible with American graphite so that all surfaces and intermediate spaces of the fibers are coated and filled out with the fatty material. The bunch of fibers thus treated is advantageously more or less 45 tightly twisted together and placed in a mold. The mold consists of a matrix having an annular recess, a central mandrel or pin and a die of corresponding annular shape. Several rings of the above mentioned 50 metallic fibrous material are advantageously placed in a mold, to fill the same. This has the advantage that the lubricating material becomes more intimately mixed with the metal and that the contacting ends 55 of the fibers are staggered, so to say, as regards each other, *i. e.* they do not lie in the

same plane. The mold when thus filled is subjected to a high pressure, about 500 kg. per square centimeter, *i. e.* 500 atmospheres; and thus a packing ring is produced having 60 a perfectly smooth exterior surface, a ring of great durability and, possessing the following advantages:—

Owing to the compression of the many 65 windings and interlaced threads of soft metal, a great number of hollow spaces are formed, which are filled with the lubricating medium. The fibers are, however, so intimately combined, by the pressure employed, that the ring produced is concrete. The material 70 possesses high tearing resistance, but is at the same time, yielding and readily conforms to varying pressure in the glands.

When the glands are tightened up the lubricating medium is pressed out of the 75 metal on to the walls of the glands, and the durability of the ring is insured by the fibrous nature of the material.

In rings of this kind a capillary effect is 80 produced which retains the lubricating medium. It is disadvantageous of the packing material hitherto known, that the lubricating material is mainly used up in the initial stage, so that the packing does not last long.

In the packing forming the object of the 85 present invention; owing to the fact that, by its nature the graphite and the lubricating material are evenly distributed friction is almost avoided. It is no longer necessary to employ a closing ring or cover, of white 90 metal.

Asbestos fibers may be mixed with the metallic fibers for special purposes.

In the accompanying drawings Figure 1 is 95 a central section through a packing ring made according to the present invention, Fig. 2 is a plan and Figs. 3 and 4 represent cross-section and side view respectively of the bunch of fibers.

Further description of the drawings is unnecessary.

The lubricating material may be added to the metallic fibers after they have been compressed, if the compressed ring is dipped in a bath of lubricating material, advantageously warmed, and allowed to remain in the same until the pores of the same are completely filled. The lubrication of the rings may be renewed in the same manner for 100 years.

I claim as my invention:—

A metallic packing ring consisting of thin,

flat, soft metal threads of sufficient length to extend approximately around the ring, twisted together to form a great number of small hollow spaces in which lubricant medium is mixed, said metal threads and lubricant having been subjected to high pressure to obtain the desired shape and form.

In testimony whereof I affix my signature in the presence of two witnesses.

FRANZ DEVENTER.
